UNITED STATES PATENT OFFICE.

CLARK F. THAYER, OF ERIE, PENNSYLVANIA.

BABY-CARRIAGE.

SPECIFICATION forming part of Letters Patent No. 717,945, dated January 6, 1903.

Application filed August 18, 1902. Serial No. 120,109. (No model.)

To all whom it may concern:

Be it known that I, CLARK F. THAYER, a citizen of the United States, residing at Erie, in the county of Erie and State of Pennsylvania, have invented certain new and useful Improvements in Baby-Carriages; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to improvements in baby-carriages, and particularly to mechanism thereon for adjusting and securing the back of the carriage-body in any desired position and retaining the shade in a horizontal position with relation to the carriage-body, and for raising and lowering the foot-rest by means of the mechanism hereinafter set forth and described, and illustrated in the accompanying drawings, in which—

Figure 1 is a vertical section of a baby-carriage embodying my invention. Fig. 2 is an enlarged detail of the mechanism when the foot-rest is up. Fig. 3 is a like detail of the same with the foot-rest being released. Fig. 4 is a like detail of the same with the foot-rest partially lowered. Fig. 5 is a like detail of the opposite side of the mechanism with the foot-rest down and the back of the body up.

In the drawings illustrating my invention, A B are the wheels and A' B' the axles, C C' the springs, C² the handles, D the carriage-body, D' the adjustable body-back, and d the foot-rest hinged to the front end of the carriage-body D, all of usual and ordinary construction.

To the bottom d' of the body D, I secure the front end of an arc of a circle E, which extends downward and backward therefrom. This arc is provided with a slot E', which terminates at its forward and upper end in a hook-shaped aperture e, below which there is a stud e' projecting from one side of said arc E. The under edge of the arc E is also provided with notches e². Pivoted to the foot-rest d there is an arm F, provided at its rear end with a downward projection F' (see Fig. 5) and with a lateral stud f, which extends through the slot E' in the arc E, and on the

outer end of the stud f there is a swinging piece f', (see Figs. 1, 2, 3, and 4,) adapted to engage the stud e' in the arc E, as and for the purpose hereinafter described. From the rod d², upon which the back D' of the carriage-body D is pivoted, an arm H extends downward and is provided with a shoe H', which engages with the upper edge of the arc E and moves freely thereon, and extending downward therefrom at the side of the arc E there is an extension h, (see Fig. 5,) adapted to engage the downward projection F' on the arm F, as particularly shown in Fig. 5, and on the rear of the shoe H' there is an extension h'. Through a guide d³ and through the extension h' on the shoe H' a rod I extends from the top of the carriage-body back D' downward and is provided on its lower end with a loop I', adapted to embrace the arc E and engage the notches e² in the lower edge thereof, and above the extension h' on the shoe H' there is a spiral spring i, which operates on the rod I to raise it, so as to keep the loop I' in engagement with the notches e² in the arc E. The loop I can be detached therefrom by pressing the rod I downward, so as to compress the spring i, which is readily accomplished by the thumb of the operator applied to the knob I² on the top of the rod I. To the upper part of the back D' of the carriage-body D, I hinge a horizontal arm J, having a clamp mechanism K, in which the shade-holder L is secured and by means whereof the shade-holder can be adjusted up and down, as desired, and to the lower part of the clamp K there is pivoted the upper end of a rod M, which extends down to and has its lower end pivoted to the rod d⁴ at the back part of the bottom of the carriage-body D, which mechanism operates when the back D' of the carriage-body is raised and lowered to at all times maintain the shade-holder arm L' in a normally horizontal position, as illustrated by dotted lines in Fig. 1. The operation of the carriage-body-back and foot-rest adjusting mechanism is as follows, viz: When the operator desires to raise the foot-rest d, the rod I is pressed downward, which moves the loop I' thereon out of the notches e² in the arc E. The carriage-body back is then moved backward and the arm H on the shoe H', engaging the downward projection F' on the rod F, moves the stud f

thereon forward and upward in the slot E' in the arc E until the stud f engages the hooked portion e of said slot, where it is held by the spring f², which operation has raised the foot-
5 rest d and secured it in an upraised position, the parts being then in the position illustrated by dotted lines in Fig. 1. The back D' can then be raised into the position shown in Fig. 2 or left at any desired angle, according to the notch e² with which the loop I' is allowed to engage. Now in case the operator desires to lower the foot-rest the back D' is again swung backward until the arm h again engages the projection F'. Then the back is
10 pressed downward until the stud f is raised up sufficiently to compress the spring f² until the swinging piece f' engages the stud e', as illustrated in Fig. 3, which operates, as
15 illustrated in Fig. 4, to raise the stud f out of the notch e and allows it to travel backward in the slot E'. Then the back D' can be raised to its normal position, so that the foot-rest d is lowered and the back D' raised, as illustrated in Fig. 1.
20 Having thus shown and described my invention, so as to enable others to make and use the same, what I claim as new, and desire to secure by Letters Patent of the United States, is—
25 1. The combination in a baby-carriage of a carriage-body, a back hinged to the rear and a foot-rest hinged to the front end of the bottom thereof, a slotted and notched arc secured to the under side of the carriage-body
30 bottom, a shoe on said hinged carriage-body back traveling on said arc, a rod having a downward projection and a pin engaging the slot in said arc and extending to and pivoted
35

on the foot-rest, and an operating-rod on the hinged back adapted to engage and be disengaged from the notches in said arc, substantially as and for the purpose set forth. 40

2. The combination in a baby-carriage, of a carriage-body, a back hinged thereto, a foot-rest hinged to the front of the body, a slotted and notched arc secured to the bottom of the body, an arm pivoted at one end to said foot-rest, a stud on the opposite end thereof operating in the slot in said arc, a shoe connected with the body-back operating on said arc, and means for securing and releasing said shoe substantially as and for the purpose set forth. 45 50

3. The combination with a baby-carriage body, of a back and a foot-rest hinged thereto, an arc having a slot and a hooked notch 55 therein and notches in the edge thereof secured to the under side of said body, an arm pivoted to the foot-rest and having a stud thereon operating in said slotted arc, a downward projection on said arm, a shoe connected with the hinged back, a downwardly-projecting arm on said shoe adapted to engage the downward projection on said arm, a swinging piece on the stud on the arm extending from the foot-rest to the slot in said arc, a 60 stud on said arc adapted to engage said swinging piece, and a rod extending downward through guides on the hinged back and on the shoe, and engaging the notches in said arc, substantially as and for the purpose set forth. 70

In testimony whereof I affix my signature in presence of two witnesses.

CLARK F. THAYER.
